UNITED STATES PATENT OFFICE

2,307,502

VAPOR ELECTRIC DEVICE AND METHOD OF
OPERATION

Newell T. Gordon and Willis E. Whitney, Schenectady, N. Y., assignors to General Electric Company, a corporation of New York

Application March 28, 1941, Serial No. 385,642

7 Claims. (Cl. 176—122)

The present invention relates to vapor electric devices, such as mercury lamps, and in particular to devices of this type which are operated at relatively high vapor pressures. Our invention is applicable with especial benefit to high pressure vapor lamps which are provided with an envelope of substantially capillary dimensions in which under operating conditions there is a pressure of at least several atmospheres. High pressure lamps are described in Bol, Elenbaas and Lemmens United States Patent No. 2,094,694, issued October 5, 1937, and in Germer United States Patent No. 2,202,199, issued May 28, 1940.

It is the object of our invention to provide an improved apparatus and a method whereby vapor devices may be maintained at a desired operating temperature. In the operation of vapor electric devices of high wattage consumption, it is necessary to carry heat away more rapidly than the natural rate of heat dissipation. The progressive increase of vapor pressure otherwise would result in correspondingly increasing the voltage necessary to operate the lamp. Assuming the lamp to be operated from a supply circuit of high reactance, it eventually would be extinguished. In that event the device would not restart until it had cooled and the vapor pressure had fallen considerably lower than the pressure at which it ceased to operate. This would result in unsatisfactory intermittent operation.

Another source of difficulty encountered in the operation of high pressure lamps is the devitrification of such parts of the vitreous envelope as are in contact with the discharge, the devitrification being especially marked in the neighborhood of the electrodes. In the forms of high pressure lamps shown in the above-mentioned Bol et al. patent in which the pressure of mercury vapor reaches many atmospheres during normal operation, the heat dissipation requirements are especially exacting.

High pressure lamps may be cooled by the circulation of water over their surfaces, such arrangement being described in Bol and Lemmens United States Patent No. 2,094,695, patented October 5, 1937. Ordinarily, high pressure mercury lamps constructed to operate with a loading of more than 200 watts per centimeter of discharge column have been water-cooled. It is inconvenient and in some cases it is inefficient to water-cool vapor electric devices. Water, although an efficient cooling medium, is subject to freezing. Also, water and other cooling fluids are subject to fouling, especially when recirculated in a closed system. Furthermore, liquid cooling

is apt to be too energetic at the region where unvaporized material, such as mercury, is present. Ordinary air cooling, that is, cooling by air circulation, such as may be produced by a fan, is not sufficiently effective, particularly in lamps in which the discharge tube is of small bore as indicated in Fig. 1 and pressures of mercury vapor of at least several atmospheres are normally present during operation.

As a consequence of our invention, we have provided improved gas-cooling means, conveniently using air as the cooling medium, by the use of which vapor electric devices may be operated at high pressures with materially higher wattage inputs than heretofore possible. Another advantageous result of our invention is a reduction of devitrification of the envelope in which a high pressure discharge occurs and which is cooled in accordance with our invention.

As will be pointed out in greater particularity in the appended claims, the main novel feature of our invention comprises a method of and apparatus for applying to a vapor electric device high velocity jets of cooling fluid, preferably air, the cooling jet having a dimension which is materially smaller than the surface which is being cooled. Another feature of our invention consists in applying such cooling jet or jets to the envelope at a region where devitrification of the envelope is apt to be most severe, that is, ordinarily adjacent the electrodes. Still another feature consists in applying the nozzle orifice so closely adjacent the surface to be cooled that the area of impingement of the jet is substantially the same or but little greater than the diameter of the jet.

Several embodiments of our invention are shown in the accompanying drawing in which Fig. 1 shows a vapor lamp and jet cooling means in side elevation; Fig. 2 shows such combination mounted in a light projector; Fig. 3 is a partly sectionalized side view on an enlarged scale of a modification in which part of a tubular lamp is coated with a light-reflecting layer; Fig. 4 is a cross section on lines 4—4 of the modification of Fig. 3; and Figs. 5 and 6 are perspective views of nozzles for furnishing cooling jets.

The lamp shown in Figs. 1, 2 and 3 comprises a tubular envelope 2 provided at opposite ends respectively with electrodes 3, 4 which may consist of tungsten. The envelope 2 ordinarily consists of vitreous or fused quartz, although heat-resisting glass also may be used. The electrode conductors 5, 6 are sealed into the envelope by a sealing glass as described in said Bol et al. Patent No. 2,094,694 and as well understood. These conduc-

tors are connected to external contact caps 1, 8. At the respective ends of the envelope 2 and surrounding the electrodes is a quantity of mercury as shown at 9, 10. Part of the mercury is contained in a pocket 11 whereby the amount of mercury is adjusted during the manufacture of the lamp. The electrodes 3, 4 project about one millimeter beyond the mercury surface. The envelope also contains a charge of starting gas, such for example as argon or neon, at a pressure of about 50 millimeters of mercury. The lamp is supported by electrically conductive supports 13, 14, on the ends of which it is held by spring clips 15, 16. Operating current is supplied by the conductors 17, 18 connected to the contact terminals 19, 20. The supports 13, 14 are mounted on an insulating base 21. Such a device may be operated at a pressure exceeding 40 atmospheres and up to 200 atmospheres and higher.

Unless the envelope of such device is energetically cooled, it will continue to rise in temperature upon being put into operation, the voltage required to operate the device rising at the same time. The rise in vapor pressure with increasing temperature would result in extinguishing the discharge after a short period of operation, or, if sufficient voltage should be available, excessive rise of internal pressure would cause it to burst.

Effective cooling and continuous operation may be obtained by directing sharply localized jets of compressed air, or other suitable cooling fluid, against the envelope of such device at the regions adjacent the respective electrodes. These jets of air, delivered by the nozzles 22, 23 and supplied by a pipe 24, should be directed substantially perpendicular to the axis of the envelope. Although nozzles such as shown in Fig. 1 are ordinarily preferred, the jets may be modified in some cases as shown at 22' and 23', Fig. 6. Satisfactory jet cooling has been afforded by maintained pressures of 10 to 40 pounds. The jets of air may have a diameter of about 50 to 80 mils. Preferably the centers of the respective jets of air are located opposite the ends of the respective electrodes. When the ends of the nozzles are lengthened to form slits, as shown in Fig. 6, a modifying effect can be exerted upon the vapor pressure and electrical characteristics of the lamp. For example, if the slit is positioned to direct the jet against a portion of the envelope adjacent unvaporized mercury, then the vapor pressure can be maintained at a lower value.

The nozzle openings should be spaced closely adjacent the surface to be cooled. A spacing of 1 to 2 millimeters ordinarily is satisfactory. Apparently a layer of warmed air, which tends to normally adhere to the surface to be cooled, must be effectively and rapidly eroded away. The jets of pressure air have an effective buffering action which we have found to be absent in the usual forms of air circulation.

Surprisingly, such localized jets adequately cool the envelope portion between the regions on which the jets impinge. As shown in Fig. 2, the described lamp and the jet-cooling adjuncts may be mounted in a light projector having a housing 26 provided with the usual reflector (not shown) and mounted on the supports 27, 28.

The lamp shown in Fig. 1 can be operated with a lighting efficiency of 86 lumens per watt of consumed electric energy and with brilliances over 50,000 candles per square centimeter. Because of this high brightness, it is well adapted for use in searchlights.

The lamp shown in Figs. 3 and 4 is in most respects similar to the lamp shown in Figs. 1 and 2, but differs therefrom by having the envelope 2 provided over approximately half of its circumferential surface with a coating 30 of light-reflecting material, such as platinum or gold, which extends longitudinally over the discharge space between the electrodes. The jets of cooling fluid delivered by two nozzles 31, 32 extend linearly 10 substantially over the entire discharge distance between the electrodes. The cooling jets of air or other suitable fluid preferably are delivered tangentially as shown in Fig. 4. In Fig. 5 is shown in perspective the nozzle 31 with its slit-shaped 15 opening 34 carried by the supply tube 35. When employing a slit-shaped nozzle the width of the slit should be materially less than the diameter of device to be cooled. In the particular case illustrated, its width is about one-fifth the diameter of the lamp. In both modifications of our invention the portion of the envelope of quartz, or other refractory material, extending between the electrodes is cooled either locally or throughout its length by the impingement of one or more high-velocity jets which, however, exert but little 20 cooling effect on the masses of mercury or whatever vaporizable material may be employed in the device. Our copending divisional application Serial No. 465,114, filed November 10, 1942, is directed to features of our invention which are embodied in the devices illustrated by Figs. 3, 4 and 5.

What we claim as new and desire to secure by Letters Patent of the United States is:

35 1. A vapor electric device comprising an envelope, electrodes therefor, a current-carrying medium including mercury in said envelope, the resulting mercury vapor being at superatmospheric pressure under normal operating conditions, cooling means including nozzles terminating respectively opposite said electrodes closely adjacent said envelope and having an opening of such small dimension that a jet of air issuing therefrom impinges exclusively on said envelope, 40 and means for supplying air thereto at a pressure sufficiently high to maintain the vapor pressure in said envelope below a predetermined discharge-extinguishing limit.

2. A vapor electric device comprising an envelope, electrodes therein spaced apart, a current-carrying medium in said device including a vaporizable material which in a condensed state surrounds said electrodes at least in part and cooling means constructed to supply jets of gas under 45 pressure directed against the parts of the envelope which are immediately adjacent said electrodes and having at least one dimension which is relatively small with relation to the surface being cooled.

3. A high pressure vapor electric lamp comprising a tubular quartz envelope, electrodes having conductors sealed into the wall of said envelope, a starting gas in said envelope, bodies of mercury therein respectively surrounding said conductors and being sufficient in quantity to produce under operating conditions a vapor pressure of at least several atmospheres and means for directing against said envelope at regions adjacent said respective mercury bodies constricted jets of cooling gas at a pressure of at least about 10 pounds having a sectional area less than the surface receiving the local impingement of said jets.

4. A high pressure vapor electric discharge device comprising an elongated tubular envelope,

electrodes having stems respectively sealed into said envelope at the ends thereof, a filling for said envelope comprising a starting gas and a material which is vaporizable at the operating temperature of said envelope, and cooling means constructed to project localized jets of compressed air against said envelope at regions adjacent said electrodes and substantially perpendicular to an axis passing through said electrodes.

5. A high pressure mercury vapor lamp comprising an elongated tubular envelope which is capable of withstanding an internal pressure of about 40 to 200 atmospheres, electrodes of tungsten therein having conductors sealed into the ends of said envelope, a starting gas at a pressure of about 50 mm. of mercury, mercury surrounding said electrodes and conductors except for a projecting tip, means for supplying air under pressure to cool said envelope, said means having constricted nozzles terminating closely adjacent to said envelope and being positioned to direct constricted jets of air locally upon discharge-carrying regions of said envelope enclosing said electrodes.

10. 6. A method of controlling the pressure in a vapor electric device which comprises a sealed envelope containing spaced electrodes and a vaporizable material, which method consists in car-

rying away heat from said envelope by the impingement of constricted jets of air thereon at regions adjacent said electrodes, the distance between said envelope and the base of said jets and the area of impingement of said jets being substantially the same as the cross section thereof, and maintaining the pressure of compressed air for said jets at about 10 to 40 pounds.

15. 7. A method of operating an electric discharge device comprising an envelope of capillary dimensions containing electrodes positioned near the ends thereof, and being provided with a starting gas and a quantity of mercury, which method consists in operating said device with an energy input of at least about 200 watts per centimeter of discharge column, cooling said device by the impingement of constricted jets of air respectively directed externally against the electrode regions of said envelope, so regulating the length of said jets that the area of impingement thereof is substantially the same as the diameter thereof, and maintaining the velocity of air delivery of said jets sufficiently high to prevent the voltage required to maintain a discharge between said electrodes from rising above 20. 25 a predetermined value.
